WRENCH

Lyal R. Boos, Kansas City, Mo.

Application August 4, 1932. Serial No. 627,481

3 Claims. (Cl. 81—169)

This invention relates to a wrench of sturdy construction and at the same time one that is efficient in removing damaged nuts.

One of the objects of this invention is to provide a wrench of such sturdy construction that it can be dropped or thrown around without material damage or injury to the wrench itself or lessening of its efficiency in removing damaged nuts.

10 A further object is to provide a wrench that is easy and efficient in operation, economical of manufacture, simple in construction, and will withstand hard usage without impairing its operation and efficiency.

15 Still another object is to provide a wrench that may be used for tightening and removing ordinary nuts as well as nuts or other screw parts formed with a socket.

A further object is to provide a wrench that 20 may also when desired be used as a hammer without impairing its usefulness as a wrench.

My invention further resides in the combination, construction and arrangement of parts illustrated in the accompanying drawing, and 25 while I have shown therein a preferred embodiment, I wish it understood that the same is susceptible of modification and change without departing from the spirit of my invention.

In the drawing:—

30 Fig. 1 is a perspective view of a wrench embodying the present invention.

Fig. 2 is a longitudinal sectional view taken along a central plane, but showing the shank of the movable jaw in elevation.

35 Fig. 3 is a perspective view of the stationary jaw and the handle, with the lower part of the rotatable operative portion spaced from the rest of the handle for the sake of clearness.

Fig. 4 is a perspective view of the movable 40 jaw and its shank.

Fig. 5 is a section on the line 5—5 of Fig. 2.

Fig. 6 is a section on the line 6—6 of Fig. 2.

Fig. 7 is a perspective of a block to be inserted and held between the jaws when the wrench 45 is to be used for a hammer.

Fig. 8 is a perspective view of a block to be held between the jaws of the wrench when the wrench is to be used for removing nuts or other parts having a socket therein.

50 Referring in detail to the drawing, it will be seen that my improved wrench comprises a handle 1, to which is securely fixed a stationary jaw 2, formed as seen in Fig. 5, with a non-circular opening 3, through which slidably extends the shank 4 of the movable jaw 5. As

seen in Figs. 2 and 4 the end portion of shank 4 opposite to that carrying the movable jaw 5 is formed with screw threads 6, which threads mesh with corresponding threads 7 in the cylindrical portion 8 of the operating grip 9, which grip is a composite member formed of the lower cylindrical portion 8 and the upper sleeve member 10. As will be seen in Fig. 3, the lower cylindrical portion 8 of the composite grip 9 is formed with the reduced diameter 11 externally threaded, and also a further reduced diameter 12, which is not threaded externally. As will be readily understood the internal threads 7 of the cylindrical member 8 extend from near the end of the member 8 throughout the length 70 of the same, and also through the internal bore of the reduced portions 11 and 12.

As seen in Fig. 2, sleeve 10 is provided at its free end with the internal threads 13, which are adapted to engage with the threads on the reduced portion 11 when the parts are in assembled position. Sleeve 10 above threads 13 is of smaller diameter to form shoulder 14, which shoulder when the parts are in assembled position has rotative sliding engagement with shoulder 80 15 of the flange 16, formed on the lower end of the hollow handle member 1.

In assembling these parts sleeve 10, which before assembling is longitudinally slidable on sleeve 1, is screwed onto the cylindrical portion 8 by means of threads 13 and the threads on the reduced portion 11, until hole 17 comes into registry with threaded hole 18, at which time screw 19 is inserted through hole 17 and screwed into hole 18, so as to secure these parts in proper 90 position. This brings shoulder 20 into rotative sliding engagement with the lower edge of flange 16, and also brings shoulder 14 of sleeve 10 into rotative sliding engagement with shoulder 15 of flange 16, thus securing the grip member 9 rotatably but non-movable longitudinally upon handle 1.

The shank 4 of movable jaw 5 is then inserted through opening 3 in the stationary jaw 2 and pushed inwardly therethrough until the threaded portion 6 engages thread 7, after which rotation of grip portion 9 in the proper direction will draw shank 4 within handle 1, and move the slidably jaw 5 toward the stationary jaw 2, either entirely thereagainst or spaced 100 therefrom any desired distance to permit entry of a nut within one of the pairs of jaws, after which the jaws are tightened on the nut by further rotation of grip 9, and as seen in Figs. 1 and 3, the jaws 2 and 5 are provided with four 105 110

different sizes of complementary members to provide four pairs of cooperating jaws to accommodate different sizes of nuts.

In Fig. 7 is shown a block of steel, or other desirable material, said block being formed with a reduced portion 21 and a head 22. When the reduced portion 21 is tightened between any one of the pairs of jaws desired, the head 22 may be used as the face of a hammer to enable the wrench to function as a hammer, when desired, and without injuring the jaws of the wrench.

In Fig. 8 is shown an elongated block 23, which may be tightened between any of the pairs of jaws desired, and used when it is desired to tighten or loosen a nut or other part formed with a socket. This hammer block and block 23 increases the range of usefulness of the wrench. It is, of course, readily understood that other sizes of block 23 may be furnished to accommodate operation upon parts having sockets of different dimensions.

While I have shown the unthreaded portion of shank 4 of movable jaw 5 as being hexagonal in cross-section, it will be understood that any other non-circular cross-section may be used as desired. The exterior surface of grip portion 9, including sleeve 10 and cylindrical portion 8, may be milled or otherwise roughened as at 24 to enable the operator to firmly grip the same with his hand during use.

Shank 4 is preferably provided at its upper end with a reduced portion 25, which is seated and welded within a corresponding opening in the movable jaw 5, thus providing a firm and rigid connection between the movable jaw and its shank. If desired, these two parts may be made integral or otherwise secured, the requirement being that they be so rigidly secured together that movable jaw 5 will not become loosened through hard use from its shank 4.

The construction described above gives a wrench of great strength and durability, and one between the jaws of which a nut even though damaged may be very tightly secured, thus resulting in a great saving of time in removal of damaged nuts as well as undamaged nuts. This tight engagement of the jaws with the nut is made possible by the large leverage produced by the operator's hand upon the composite grip member 9, which is located at the lower or free end of the handle.

Having now described my invention.

I claim:—

1. A wrench comprising a handle provided at one end with a stationary jaw and at the other end with an annular flange, a grip member having an elongated reduced bearing portion extended into the open flanged end of said handle and having rotative engagement therewith, a sleeve encircling the grip member and also encircling an adjacent portion of said handle at a position concentric with said bearing portion, said sleeve being normally fixed with respect to said grip member and having an annular shoul-

der rotatively engaging said flange, and a movable jaw having a shank adjustably engaging said grip member, said shank and said stationary jaw having complementary means constructed and arranged to prevent relative rotation thereof.

80

2. A wrench comprising a tubular handle of circular cross section provided at one end with a stationary jaw and at the other end with an annular flange, said jaw having an opening therethrough of polygonal cross section and in register with a contiguous open end of said handle, a grip member having an externally threaded portion and also provided with an elongated reduced bearing portion, said bearing being extended into the open flanged end of the handle and having rotative engagement therewith, said reduced bearing portion providing a shoulder-like seat for the flanged end of said handle, a sleeve having a threaded portion engaging the threaded portion of the grip member and also having a portion encircling said handle at a position concentric with said bearing portion, said sleeve having an internal annular shoulder rotatively engaging said flange, means for normally preventing relative movement of the grip member and said sleeve, and a movable jaw having a shank adjustably engaging said grip member, said shank being of a section complementary to that of the opening in said stationary jaw and so arranged as to prevent relative rotation of said shank and said jaw.

85

3. A wrench comprising a grip member having an internally threaded bore and provided at one end with an exteriorly threaded reduced portion, an elongated reduced bearing portion cooperating with said reduced portion to provide an annular shoulder, a handle provided at one end with a stationary wrench jaw and at its other end with an annular flange, said flanged end being open and enclosing the bearing portion of the grip member so as to have rotative engagement therewith, a coupling sleeve having threaded engagement with the externally threaded portion of the grip member and having another portion enclosing said handle at a position concentric with said bearing portion and also having an annular shoulder so positioned as to engage said flange, whereby the handle and the grip member are freely rotatable with respect to each other and relative longitudinal displacement is prevented, means for normally preventing relative movement of the coupling sleeve and the grip member, and a movable jaw member having a shank extended axially through the handle and provided with a complementary portion engaging the threaded bore of the grip member, said shank and said stationary jaw having complementary means so constructed and arranged as to prevent relative rotation of the movable jaw with respect to the stationary jaw.
